UNITED STATES PATENT OFFICE.

ROBERT L. HORSLEY, OF MEMPHIS, TENNESSEE.

DEVICE FOR DRAWING THE ENDS OF A BAND OR BALE TIE TOGETHER.

Application filed April 8, 1922. Serial No. 550,655.

To all whom it may concern:

Be it known that I, ROBERT L. HORSLEY, a citizen of the United States, residing at Memphis, in the county of Shelby and State 5 of Tennessee, have invented certain new and useful Improvements in Devices for Drawing the Ends of a Band or Bale Tie Together, of which the following is a specification, reference being had therein to the 10 accompanying drawings.

This invention relates to a device for drawing the ends of a band or "bale tie" together, and has for its object the provision of simple and efficient means for drawing 15 the ends of a band or "bale tie" together, so that they can be fastened by an ordinary buckle.

Another object of the invention is the construction of a simple and efficient device 20 for fastening a band or "bale tie" upon a bale of cotton, or the like, by drawing the ends of the band close together and then, while in this taut or drawn condition, placing a fastening device on the ends, where- 25 upon the drawing device will be removed from the bale of cotton.

With these and other objects in view, my invention comprises certain novel combinations, constructions and arrangements of 30 parts as will be hereinafter described, illustrated in the accompanying drawings, and more particularly pointed out in the appended claim.

In the drawings:

Figure 1 is a view, in elevation, of a bale 35 of cotton showing my device in position thereon, for drawing the ends of a band or "bale tie" together.

Figure 2 is a top plan view of my device 40 showing the same in the position that the parts are placed or assembled when the ends of the band are brought together, with the buckle, commonly known as an "arrow buckle," in place thereon.

Figure 3 is a front view of the device 45 shown in Fig. 2, with the handle of the screw removed.

Figure 4 is a fragmentary, perspective view of the device.

Figure 5 is a plan view showing the ends 50 of the band or "bale tie" in position upon the "arrow" buckle.

Referring to the drawings by numerals, 1 designates a bale of cotton around which is 55 placed the band or "bale tie" 2; this band can be made of any material, such as a strip

of flat metal or a wire, as the operator desires. I will designate this element 2 as a "band" throughout the specification and claim, using the word "band" in a broad 60 sense.

My drawing device, for bringing the ends of the band 2 together, comprises two elements or blocks 3; each block 3 includes a body 4, from one side of which body 4 ex- 65 tends a tapering flange or fin 5. In the inner portion of the fin 5 I form a buckle-receiving slot 6. When the two blocks 3 are placed upon a bale 1 screw 7 is threaded through the bodies 4, and by operating han- 70 dle 8, of screw 7, the blocks may be brought together, Fig. 2, or spread apart, Fig. 1. It is to be noted that to accomplish this function the screw 7 is provided with the usual right and left threads. 75

To keep the cloth or covering of the bale 1 from puckering or projecting up between the inner faces of the blocks 3 as the blocks are secured together (Fig. 2), I place a flat protecting plate 9, under the blocks; plate 80 9 is fastened to one of the blocks by chain 10, and therefore, cannot be accidentally misplaced or lost.

The ends 2^a, of the band 2, are looped around the fins 5 next to bodies 4, with the 85 extreme loose end 2^b (Fig. 3) underneath; consequently, as the blocks are screwed together, the tautness of the band will cause the ends 2^b to tightly press against the bale 1, as well as plate 9, preventing displacement 90 of the looped ends 2 from off the fins prior to the placing of the buckle 10^a in the slots 6 and upon the looped ends 2^a. As seen in Fig. 3, the looped ends are in engagement and the mouth of the buckle 10^a can be 95 slipped over these engaging portions and then turned at right angles, with the ends of the bands securely placed upon the buckle, whereupon screw 7 can be rotated to cause the blocks 3 to move apart, and 100 then the drawing device can be quickly removed off the bale.

It is to be noted that I have provided a simple and efficient device for drawing the ends of a band together for allowing a 105 buckle to be placed upon the ends, whereupon my device can be removed and the ends permanently secured together. My de- 110 vice is particularly efficient for fastening the ends of a broken band or "bale tie" together.

While I have described the preferred em-

bodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claim.

10. What I claim is:

In a device of the character described, a pair of blocks each having a body portion provided along one side with an outwardly-extending flange for passing through a loop formed at the end of a bale strap with the

free end portion of the strap beneath the flange, the flange being provided with a recess opening through its outer side edge face and inner end face whereby a fastener clip for the ends of the strap may be passed into the recesses of the flanges of said blocks and engaged with the loops of the strap, and means for retaining the blocks in end to end relation to each other and moving the blocks towards and away from each other. 20 25

In testimony whereof I hereunto affix my signature.

ROBERT L. HORSLEY.
